Application February 25, 1942, Serial No. 432,357
In Great Britain February 19, 1941

7 Claims. (Cl. 198—54)

This invention concerns improvements relating to apparatus for feeding from a container, cartridges which have a larger cross-sectional area at one end than at the other and which have a main body portion adjacent the larger end.

According to the invention there is provided apparatus for feeding cartridges of the kind described, comprising a receptacle having an outlet and a downwardly directed bottom and an end wall which converge towards the outlet, the cartridges being arranged to move sideways towards and through the outlet, and means at the bottom of the container to impart a rotational movement to the cartridges as they move towards the outlet. The means to impart a rotational movement to the cartridges may comprise an endless band having its upper run passing along the bottom of the receptacle, the band being of such a width as to engage only a portion of the length of cartridges lying thereon.

Further according to the invention there is provided apparatus for feeding cartridges comprising a receptacle, a stationary bottom and an end wall, an outlet formed between the end wall and the stationary bottom, which latter slopes downwardly to the outlet, a conveyor-surface arranged to move over said stationary bottom towards the outlet, the conveyor-surface being so located in the container as to engage the body portions of cartridges so that their longitudinal axes are transverse to the direction of movement of the conveyor-surface and so that their large ends are clear of the stationary bottom of the container. A drag-member may be disposed within the container and arranged to engage the nose of a cartridge which is engaged by the conveyor-surface or endless band, the engagement of the cartridge by the drag-member being at a position which is near the smaller end of the cartridge, for the purpose of reducing the tendency of such a cartridge to point its smaller end in the direction of movement of the conveyor surface. A positively driven transfer-device, (e. g. a transfer-device which is wholly located outside the container) may be adapted to receive cartridges from a conveyor-surface and move the cartridges away from the container and to apply an impedance to the cartridges at the outlet. The conveyor-surface may comprise an endless band, the upper run of which is interrupted by passing the band around an element, the latter being so disposed as to divide the upper run into two parts to form an obtuse angle, one of said parts comprising the transfer-device. Guide

means may be provided to restrain the conveyor-surface against aberrance due to the weight of cartridges resting thereon.

The guide-means above referred to may comprise flanged pulleys and the band, in such cases, is passed between the flanges of said pulleys to restrain the band against aberrance due to the weight of the cartridges resting thereon.

One embodiment of the invention will be described by way of example with reference to the accompanying drawings which show apparatus for feeding cartridges and in which:

Figure 1 is a front elevation of the apparatus.

Figure 2 is a plan of Figure 1.

15 Referring to the drawings, the apparatus is primarily designed for cartridges 2, Figure 2, of a fairly large calibre, e. g. cartridges containing a half inch bullet, but the apparatus can also be designed to be employed either with smaller or larger cartridges if desired.

20 A box-like container or hopper 24 for the cartridges has opposed side walls 115 which are spaced apart by a distance which is slightly greater than the length of the cartridges to be placed therein, and end walls 37 secured to the side walls and a stationary bottom wall 116 fixed to the side walls. As shown in Figure 1, the wall 31 comprises three parts, viz. a vertical part 37A, a slightly sloping part 37B and a steeply sloping part 37C. The convergence of the bottom wall and the end wall helps to ensure that the articles at the outlet are properly trued up since they will be engaged by articles engaging the bottom and end walls respectively. The bottom wall 116 of the container passes beneath the lower end of the end wall 37 so that an outlet 117 is provided beneath the end wall and the bottom of the container through which outlet cartridges can pass from the container 24. An endless band 25 is arranged to run over guide-pulleys 118, 119, 120, 121, 122, 123, some of the pulleys being flanged for a purpose described later. The band passes between the flanges of the pulleys and a part 124 (Figure 1) of the upper run of the band comprises a conveyor-surface which moves over the bottom wall 116 of the container. At the lower end of the bottom wall of the container and adjacent thereto there is provided the small guide-pulley 120 over which the band passes downwardly around the larger pulley 122. From this pulley the band passes upwardly and over the further small pulley 121, after which the upper run of the band continues in an upwardly inclined direction and comprises a transfer-device 125 (Figure 1) which is adapted to receive cartridges

as they issue from the outlet of the container and to move the cartridges so received to the position 126 to which they are to be delivered. The transfer-device helps to prevent the article from emerging too fast from the outlet and thus ensures a better regulated or controlled feed. The apparatus shown forms part of the machine described in my concurrently filed United States application Serial No. 432,358, in which case the cartridges are delivered to a fluted drum. Part 10 of this drum is indicated in chain lines in Figure 1 and marked with the reference 4. After the cartridges have been delivered to the desired position the band passes round the pulleys 119 and 123 and returns to the upper end of the bottom of the container. The tension of the band may be controlled by means of adjustable jockey-pulleys in any desired manner, but as shown in Figure 1, the pulley 123 is adjustable in guides 227 by screws 128 for this purpose. The two small pulleys 120 and 121 are arranged to be as close together as possible and a line joining their centres is substantially horizontal. By this arrangement of the two small pulleys 120 and 121, and the larger one 122 which is located beneath them, the upper run of the band is interrupted without any substantial interference being encountered while cartridges are passing from the conveyor-surface 124 to that part 125 of the band which constitutes the transfer-device. In order that each part of the upper run of the conveyor shall operate satisfactorily to drive the cartridges forwardly, the band is driven from two positions. The pulley 118 over which the downwardly directed part of the upper run of the band passes when entering the container, is positively driven and the pulley 119 at the delivery end of the upwardly directed part of the upper run, that is the part 125 of the band which constitutes the transfer-device, is also positively driven. Since the band is one continuous band, the peripheral speed at which these two pulleys are driven is the same.

As previously mentioned the apparatus shown forms part of the machine described in the specification referred to and parts of the driving arrangements of said machine are illustrated in the accompanying drawings to show how the band 25 may be driven. Referring to Figure 2, a shaft 66 journalled in the frames of the apparatus has a sprocket wheel 65 thereon which may be driven by a motor or alternatively the shaft may be driven by the hand wheel 169 all as described in said specification. A small gear wheel 69 on the shaft drives a large gear wheel 10 on a shaft 11 also journalled in the frames. A large sprocket wheel 72 is fixed to this shaft and a chain 73 on said wheel passes around other sprocket wheels 74 and 75. The sprocket wheel 74 is fixed to a shaft 127 which is journalled in the frames and has the pulley 118 fixed thereto while the sprocket wheel 75 is fixed to a shaft 76 rotatable in the frames and carrying the pulley 119.

Above the transfer-part of the upper run of the band there is provided a guide, or a plurality of guides 228, beneath which the cartridges pass, the guide being provided to ensure that the cartridges are retained in position on the band.

The band, as it moves through the container, is so arranged within the container that it engages only a portion of the length of the body portions 2B, Figure 2, of the cartridges so that they lie transversely to the direction of movement of the conveyor-surface and so that their larger ends are clear of the stationary bottom of the 75

container. Thus as the band 25 is offset with respect to the mid-length of the cartridge, a force is applied to the cartridges by the driving action of the band and this force, by causing the cartridges to rotate, tends to prevent the cartridges from tending to point downwardly into the container owing to their weight with their smaller ends pointing in the general direction of movement of the band. At the opposite side of the container and running parallel to the band 25 there is secured to the bottom thereof a drag-member which comprises a bar 129 (of which only a fragment is shown in Figure 2), arranged to engage with the smaller ends 2A of the cartridges and this bar, being a stationary member, also assists in reducing the tendency of the cartridges to lie aslant the band and to point down nose first as they are being fed downwardly to the outlet of the container.

The operation of the apparatus is as follows, a mass of cartridges are placed into the container with their longitudinal axes transverse to the direction of movement of the conveyor-surface (i. e. as shown by the single cartridge illustrated in Figure 2) and with the larger ends clear of the stationary bottom of the container. The downward movement of the conveyor-surface tends to rotate the cartridges. By this means, the lower cartridges are fed one at a time through the outlet 117 on to the transfer-device 125. It will be appreciated that since cartridges are heavy, the weight of a mass of cartridges in a hopper would cause a block at the exit of the hopper if the bottom were horizontal. The sloping bottom ensures that the cartridges by their weight exert pressure along the bottom towards the outlet. Due to the presence of gaps between cartridges at their noses, there is a tendency due to the weight of a mass of such cartridges in a hopper, for some cartridges to slew nose down into these gaps when the cartridges are in motion, as when being fed from a hopper. To prevent this the endless band which runs along the sloping bottom of the hopper in the construction described, provides a driving action which rotates the cartridges in an anticlockwise direction as viewed in Figure 1, and this rotation reduces the tendency of this slewing of some of the cartridges. The fixed plate or drag member which engages the noses of the cartridges also provides an additional element which co-operates to prevent the nose of the cartridges from pointing towards the outlet.

As has already been described, the endless band 25 is made narrow within reasonable practical limits. By having a narrow band the differences in the diameters of a cartridge at the edges of the band are less than if the band were wide: therefore a narrow band causes less tendency for the cartridges to slew round due to the driving action of the band. It will be seen, therefore that since the invention is concerned with dealing with a tapering, heavy article, namely a cartridge, the rotation of the cartridges plus the fact that they are rotated by a narrow band, are two features which jointly contribute to prevent slewing. In addition, by reason of the fact that the cartridges lie on a sloping bottom in the hopper, the row of cartridges at the bottom of the hopper is taken away while the cartridges are being continually rotated, and this keeps other cartridges in the hopper in a substantial state of rotation about their individual axes at all times, so tending to prevent the cartridges going down nose first and thereby causing a complete stopping up. The transfer-device moves the cartridges upwardly

and delivers them to the desired position. Due to the fact that the band is offset with respect to the mid-length of the cartridges, there is a tendency for the band to wander laterally due to the weight of the cartridges in the container, but as the band moves between the flanges provided on the guide-pulleys around which the band passes, this tendency is greatly minimized. The position of the smaller pulleys 120 and 121 around which the band passes adjacent the outlet of the hopper is such that the transfer-device is wholly outside the container, and the portion 125 of the conveyor-surface outside the hopper continues to feed the articles to a position which is outside the container.

It is found that due to the convergence of the bottom and end walls, and the movement and arrangement of the band 25, the cartridges with their larger ends clear of the bottom wall 116, travel to the outlet along the bottom of the conveyor while rotating in the opposite direction to that of the rollers 118 and 120. In this way the cartridges are maintained trued up and cartridges are taken away from the mass along the bottom of the receptacle, and as cartridges are so taken away, others move to the rear of the stream moving along the bottom towards the outlet.

An important feature of the invention is the fact that the cartridges after leaving the outlet of the hopper are caused to move upwardly on what has been called the transfer device. This transfer device is a practical way of carrying out the basic idea of applying a force opposing that which moves the cartridges from the hopper. If there were no such opposing force there would be nothing to ensure that the cartridges leaving the hopper are under proper control and they would tend to rush out. The transfer device provides the required resistance to ensure that the cartridges leaving the hopper are under proper control. This resistance is caused by the weight of the cartridges on the upwardly sloping surface of the transfer device in the example being described, and the cartridges are caused to move up the inclined surface, by the force from those being fed on the downward surface of the hopper. In other words the opposed force of the transfer device helps to ensure that the cartridges move out slowly from the hopper outlet and thus enable the band in the hopper to effect the rotational movement of the cartridges in the reverse direction to that which they would have if they merely rolled down the sloping bottom. If the opposing force were not provided the cartridges would first start to rush out of the outlet uncontrolled and with gaps between them, which would very quickly result in some cartridges slewling round and so obstructing the free passage from the outlet and causing a jam.

What I claim as my invention and desire to secure by Letters Patent is:

1. Apparatus for feeding cartridges, comprising a receptacle having an outlet and a downwardly directed bottom and an end wall which converge towards the outlet, the cartridges being arranged to move sideways towards and through the outlet, and means at the bottom of the container to impart a rotational movement to the cartridges as they move towards the outlet, the last said means comprising a rotating element arranged to engage only a portion of each cartridge lying thereon.

2. Apparatus for feeding cartridges, comprising a receptacle, a stationary bottom and an end wall, an outlet formed between the end wall and the stationary bottom, which latter slopes downwardly to the outlet, a conveyor-surface arranged to move over said stationary bottom towards the outlet, the conveyor-surface being so located in the container as to engage the body portions of cartridges so that their longitudinal axes are transverse to the direction of movement of the conveyor-surface and so that their large ends are clear of the stationary bottom of the receptacle and arranged to impart a rotational movement to the articles as they move towards the outlet.

3. Apparatus for feeding cartridges, comprising a receptacle having an outlet and a downwardly directed bottom and an end wall which converge towards the outlet, the cartridges being arranged to move sideways towards and through the outlet, and means at the bottom of the container to impart a rotational movement to the cartridges as they move towards the outlet, said last named means comprising an endless band having its upper run passing along the bottom of the receptacle, the band being of such a width as to engage only a portion of the length of cartridges lying thereon.

4. Apparatus as claimed in claim 3, wherein a drag member is disposed within the receptacle and arranged to engage a cartridge which is engaged by the conveyor-surface of the endless band, the engagement of the cartridge by the drag-member being at a position which is near the smaller end of the article.

5. Apparatus as claimed in claim 3 wherein a positively driven transfer-device is adapted to receive cartridges delivered from said outlet and move the cartridges away from the receptacle and to apply an impedance to the cartridges at the outlet.

6. Apparatus for feeding cartridges, comprising a receptacle having an outlet and a downwardly directed bottom and an end wall which converge towards the outlet, the cartridge being arranged to move sideways towards and through the outlet, and means at the bottom of the container to impart a rotational movement to the cartridges as they move towards the outlet, said last named means comprising an endless band conveyor, the continuity of the upper run of said conveyor being interrupted so as to divide the same into two parts forming an obtuse angle, one of said parts lying within said receptacle and the other of said parts lying wholly outside of said receptacle and comprising a transfer device receiving cartridges from said receptacle and impeding the discharge of cartridges from said outlet.

7. Apparatus for feeding cartridges, comprising a receptacle having an outlet and a downwardly directed bottom and an end wall which converge towards the outlet, the cartridges being arranged to move sideways from the outlet, means at the bottom of the container to impart a rotational movement to the cartridges as they move towards the outlet in a direction reverse to that which they would have if they rolled out, and means located beyond the outlet to impede the movement of cartridges being discharged from said outlet, the last said means comprising a rotating element arranged to engage only a portion of each cartridge lying thereon.

FRANK PARRY.
